UNITED STATES PATENT OFFICE

2,272,169

ONE-WAY CLUTCH

Albert J. Granberg, Berkeley, Calif., assignor to
 Granberg Equipment, Inc., Emeryville, Calif.,
 a corporation of California

Application June 5, 1939, Serial No. 277,395

5 Claims. (Cl. 192—45.1)

My invention relates to a one-way clutch and more particularly to a one-way clutch ideally adapted for use in a twin pump assembly.

Among the objects of my invention are: To provide a simple and efficient one-way clutch; to provide a means for automatically and selectively operating one of two pumps in a twin pump unit in accordance with the will of an operator; and to provide a clutch means for selecting one pump and excluding the operation of the other in a twin pump unit.

Other objects of my invention will be apparent or will be specifically pointed out in the description forming a part of this specification, but I do not limit myself to the embodiment of the invention herein described, as various forms may be adopted within the scope of the claims.

Referring to the drawings:

Fig. 1 is a diagrammatic plan view of one preferred form of a twin pump unit embodying my invention, together with a wiring diagram for the operation thereof.

Figs. 2 and 3 are cross-sectional views, taken as indicated by the lines 2—2 and 3—3, respectively, in Fig. 1.

Fig. 4 is a longitudinal sectional view, taken as indicated by the line 4—4 in Fig. 2.

Fig. 5 is a top plan view of an optional gear drive.

Fig. 6 is a sectional view, taken as indicated by the line 6—6 in Fig. 5.

Fig. 7 is a longitudinal sectional view, taken as indicated by the line 7—7 in Fig. 6.

Referring directly to the drawings for a more detailed description of the preferred form of my invention as shown in the various figures, and referring first to Fig. 1, a motor 1 drives a pinion 2 through flexible coupling 3. Pinion 2 is enclosed in gear case 4 in which is mounted a cross-shaft 5 carrying a bevel gear 6 meshed with pinion 2. Cross-shaft 5 extends outside of the casing on both sides thereof. On each end of the cross-shaft is mounted a left clutch 9 and a right clutch 10. Right clutch shaft 11 connects through right flexible coupling 12 to right pump 14, which may be of any known type, although I prefer to use the type of pump described and claimed by me in my prior application for United States Letters Patent entitled "Pump," Serial No. 247,765, filed December 27, 1938.

In the left hand side of the gear case 4 the clutch shaft 15 of clutch 9 leads through flexible coupling 16 to left pump 11, which may be a duplicate of pump 14. Motor 1 is supplied with

power by line 19, preferably from three phase alternating current mains 20 through the customary fuse box 21 and a reversing switch 22. Thus, motor 1 can be driven in either direction in accordance with the position of the reversing switch handle 24, which may be placed within reach of a fuel loading operator at any desired distance from the pump unit itself.

The selective action of the pump unit above described depends upon the selective action of clutches 9 and 10. These clutches are of the so-called "free wheeling" type, which will drive in one direction but which will disconnect when running in the opposite direction.

The internal construction of these clutches may be more readily understood by reference to Figs. 2, 3 and 4. Pump cross-shaft 5, on either side of casing 4, is provided thereon with a pair of eccentric cams 26 and 27, mounted side by side. Fitting cam 26 is a clutch shoe 29, and fitting cam 27 is a second clutch shoe 30. These clutch shoes are provided on the periphery thereof with clutch surfaces 31 which are curved to engage the inner surface of outer casing 32 of the clutch assembly. Outer casing 32 is connected through fitting 34 to right and left pump shafts 11 or 15, in accordance with the side on which the clutch is being used. Thus, when the shaft 5 is being rotated in one direction, cams 26 and 27 throw the clutch shoes 29 and 30 outwardly until the clutch surfaces 31 on each clutch shoe engage and lock to the inner surface of clutch casing 32, thereby driving the connected pump 14 or 17. When shaft 5 is rotated in the opposite direction, however, cams 26 and 27 draw the clutch shoes together until they contact on center line 35, which prevents further movement toward each other. The contact between clutching surfaces 31 and the interior of casing 32 is broken and the shaft 5 ceases to drive the connected pump.

Clutches 9 and 10, mounted on shaft 5, give reverse action with respect to the pumps 14 and 17 because the pumps face each other, so that when the pump on one side is being driven the pump on the other side is disconnected. Thus, the pump to be driven can be selected by selecting the direction of rotation of motor 1, which is done by the operator by remote control operation of reversing switch handle 24. It is impossible, in this manner, to drive both pumps from the same motor, thus preventing overloading of the motor. The time required for loading is reduced, as it is not necessary for the operator to go from a loading rack to the pump

house to change clutches from one pump to another in order to change liquid flow at the loading rack. Either of the pumps can be selected at will from the loading platform.

In Figs. 5, 6 and 7 I have shown a modification of my unit, utilizing a central spur gear 50 mounted on the shaft of motor 1, driving lateral spur gears 51 and 52. Here, the gears 51 and 52 are journaled to ride freely on pump shafts 11 or 15, and clutch casing 32 is made an integral part of each lateral spur gear. Clutch casing 32, in this case, is preferably closed by an end plate 54, providing a bearing 55 for the end of shafts 11-15. Cams 26 and 27 are mounted on pump shafts 11 or 15, clutch shoes 29 and 30 are mounted on the cams, as described above, and thus the entire clutch assembly is supported on the pump shaft without additional bearings.

The selective operation of the free wheeling clutches is exactly as described above for the bevel gear drive, in that one of the clutches will drive one of the pumps when the motor 1 is running in one direction, and the other clutch will drive the other pump when the motor direction is reversed. At no time can both pumps be operated at the same time.

While I have illustrated gear drives for the two pumps, it will be obvious to those skilled in the art that direct drive can be used, with the clutches placed, one on each end of the motor shaft.

Thus, it will be seen that I am able to select one of two pumps to be driven by a single motor, by simply reversing the direction of rotation of the motor, and this reversal of rotational direction can easily be accomplished at a distance by the use of a reversing switch in the main power supply line to the motor.

I claim:

1. A clutch comprising a drive shaft, a pair of circular cams fastened in opposite eccentricity on said shaft, a clutch casing rotatably bearing at one end thereof on said drive shaft and extending outwardly and then over said cams to define a clutch space, and having an interior surface concentric with said shaft, at the other end thereof, said casing having a central bearing for supporting an end of said shaft, a pair of shoe plates each having a bearing aperture rotatably fitting one of said cams, said plates extending laterally in opposite directions from said cams, a shoe having a face of substantially the same curvature as said internal surface and opposed thereto mounted on each shoe plate, said shoes being engaged and disengaged with said surface in accordance with the direction of rotation of said shaft with respect to said casing, and a driven member concentrically mounted on said casing.
2. Apparatus in accordance with claim 1 wherein said driven member is a gear forming a part of said casing.
3. Apparatus in accordance with claim 1 wherein said driven member is a shaft coaxially attached to said casing.
4. Apparatus in accordance with claim 1 wherein said shoe plates have opposed inner edges making contact in disengaged position.
5. Apparatus in accordance with claim 1 wherein each of said shoes have faces of less than 180° of arc each and are held on said cams only by having end faces terminating adjacent each end of said casing to prevent axial movement.

ALBERT J. GRANBERG.
